UNITED STATES PATENT OFFICE.

LUDWIG HESS, OF NEW YORK, N. Y.

PROCESS FOR PRODUCING PRINTED MUSIC-SHEETS.

1,112,450.

Specification of Letters Patent.

Patented Oct. 6, 1914.

Application filed May 10, 1912. Serial No. 696,352.

To all whom it may concern:

Be it known that I, LUDWIG HESS, a subject of the Emperor of Germany, and a resident of the borough of Manhattan, city, county, and State of New York, have invented certain new and useful Improvements in Processes for Producing Printed Music-Sheets, of which the following is a specification.

10 This invention relates to certain new and useful improvements in processes for producing printed music sheets.

By the use of my improved process we are not only enabled to produce prints equal in artistic effect to that produced by engraving, and to save valuable time over any method at present employed, but the negative or reverse sketching on a tinned lead plate by a skilled workman is entirely eliminated; the designer, who by the use of my process requires very little preliminary training, being enabled to make a positive or natural sketch with simple utensils, thus effectually reducing the cost of both labor and materials. Furthermore, in case errors are made by the designer, they may be readily and easily erased by means of a glass eraser, and correction may be made without in any way affecting or defacing the prints subsequently made in accordance with the sketch. Furthermore, the transparent sheet which, in carrying out my process, has the music imprinted thereon may be employed over and over again, thus avoiding the necessity of storing unmelted zinc plates.

In general terms, my invention consists in first taking a sheet of transparent paper of suitable size, producing on one side of such sheet with non-transparent ink the staff lines and other music symbols, placing such sheet face downwardly upon a suitably prepared printing surface, subjecting said sheet and surface to the action of strong light, developing such printing surface in the usual well known manner and then printing from the surface so produced.

More particularly my invention consists in taking a sheet of transparent paper provided with transparent vertical and horizontal hatching lines, printing upon one side of such transparent sheet with non-transparent ink the staff lines, then lightly sketching the music symbols thereon, and then stamping by means of a metal stamp inked with non-transparent ink the music symbols so sketched, placing the said trans-

parent sheet face downwardly upon a suitably prepared zinc plate, subjecting said sheet and plate to the action of strong light to form a negative, finishing the negative 60 and printing therefrom.

In the accompanying drawings in which similar reference characters designate corresponding parts throughout the several views, Figure 1 is a plan view of a transparent sheet provided with transparent vertical and horizontal cross-hatching lines; Fig. 2 is a plan view of a portion of such sheet after the staff lines are imprinted thereon; Fig. 3 is a view similar to Fig. 2 after the designer sketches the notes and other symbols from the composer's manuscript thereon; Fig. 4 is a view similar to Figs. 2 and 3 after the stamping of the music symbols in opaque ink; Fig. 5 is a section indicating a transparent sheet placed face downwardly over a suitably prepared zinc plate; Fig. 6 is a side elevation of a stamp employed in my improved process; Fig. 7 is another side elevation at right angles to Fig. 6; Fig. 8 is a top view of the stamp; and Fig. 9 is a plan view of the printing surface of the stamp.

Referring now to the accompanying drawings, and following out the preferred form 85 of my invention, I take a transparent sheet of paper or other suitable material designated A, into which sheet is preferably imprinted transparent vertical and horizontal hatching lines represented by the light black 90 lines *a*. These lines may be imprinted into the paper or other material in any manner such as by the use of a stencil or other suitable utensil or utensils.

I proceed to print upon the sheet thus produced with non-transparent or opaque ink the music staff lines, such as I have designated *b* in Figs. 2 to 4 inclusive. I then proceed to copy from the manuscript of the composer by sketching with a pencil or other suitable utensil symbols of music, using measures and compasses as in the engraving process heretofore employed except that the copying may be done by a person having very little preliminary training, such 105 sketched music symbols being represented in Fig. 3 by the light lines designated *c*. The pencil sketch is then inked either by hand or by means of music stamps or a music writing machine, in any event using 110 non-transparent or opaque ink. In the preferred form, and to produce the best results

in the saving of time and labor, I use music stamps F illustrated in Figs. 6, 7, 8 and 9, hereinafter described.

- The stamp F comprises a base or stamping portion *f* of metal or other suitable material, having the note or other symbol represented thereby engraved or raised in or on its surface, a thin flat vertical handle *f'* squared at its edges the thickness of such handle being approximately equal to the space between the cross-hatching lines *a* so that the same may be employed as a vertical guide in stamping the symbol on the music sheet and a transverse guide bar *f*', also having a width approximately equal to the distance between the cross-hatching lines *a* and disposed at right angles to the handle *f'*. By the use of this stamp I am enabled to accurately position or place the symbol represented by the stamp with respect to the staff lines. Of course in applying symbols to the transparent sheet on which the staff lines are imprinted the horizontal bar will be held parallel to the staff lines and the handle parallel to the cross-hatching lines between which or on which it is desired to place the symbol. With a little practice such symbols may be positioned with great accuracy.
- 30 The top of the handle preferably bears the type of the symbol represented thereby so that visible and positive representative characters will appear before the stamper at all times, and if desired these stamps may be arranged in a type case, the outside of which shows the corresponding symbols, and stamps will of course be supplied to the operator in various sizes conforming to all sizes of staff lines and spaces in use.
- 40 Having now produced a transparent sheet with transparent vertical and horizontal hatching lines, and with the staff lines and music symbols in opaque or non-transparent ink, I proceed to place the transparent sheet 45 so prepared upon a metal plate suitably prepared with chromate of potash or other suitable chemical and subject the same to the action of strong light, then develop such metal plate in the usual manner so that after 50 a suitable period of such subjection to light

and subsequent development the staff lines and symbols will appear upon the metal plate in relief. These plates may then be further finished so as to eliminate all rough surfaces, whereupon music sheets may be 55 printed from the same. The sheets thus produced will be perfect in all details and as clear, distinct and equal in appearance to music sheets produced by the engraving process.

Having described my invention, I claim:

1. The process of producing music sheets which consists in taking a sheet of transparent paper dividing the surface of said sheet into minute sections by providing the same with transparent vertical and horizontal hatching lines, printing upon one side of such transparent sheet with non-transparent ink the music staff lines and other music symbols, placing the transparent sheet face downwardly upon a suitably prepared printing surface, subjecting said sheet and surface to the action of strong light to form a negative, developing said negative plate and printing therefrom.

2. The process of producing music sheets which consists in taking a sheet of transparent paper dividing the surface of said sheet into minute sections by providing transparent vertical and horizontal hatching lines thereon, printing with non-transparent ink upon one side of such transparent sheet the music staff lines, sketching the music symbols thereon in pencil, stamping by means of stamping devices inked with non-transparent ink the music symbols so sketched, placing the said sheet face downwardly upon a suitably prepared printing surface, subjecting said sheet and surface to the action of strong light to form a negative, 85 developing the negative and printing therefrom.

In witness whereof, I have signed my name to the foregoing specification in the presence of two subscribing witnesses.

LUDWIG HESS.
